CLAIM

The ornamental design for a welding visor, as shown and described.

DESCRIPTION

FIG. 1 is a first perspective view of a welding visor according to one embodiment of the invention.

FIG. 2 is a front view of the welding visor of FIG. 1.

FIG. 3 is a rear view of the welding visor of FIG. 1.

FIG. 4 is a right side view of the welding visor of FIG. 1.

FIG. 5 is a left side view of the welding visor of FIG. 1.

FIG. 6 is a top view of the welding visor of FIG. 1; and,

FIG. 7 is a bottom view of the welding visor of FIG. 1.

The broken lines showing portions of the rear side of the visor are included for the purpose of illustrating a portion of the welding visor that form no part of the claimed design.
